WINDOW STRUCTURE

Hans J. Snobeck, Chicago, Ill.

Application July 20, 1953, Serial No. 369,157

9 Claims. (Cl. 20—52.2)

This invention relates to improvements in window structures and more particularly relates to window structures in which the window sash may slide along its guideways to open and close the window and may swing inwardly for cleaning from the inside and for ventilation purposes.

An object of my invention is to provide a novel and improved draft-free window structure mounting the window sash to be pivoted to an open position for ventilation purposes and to afford a means for washing the window from the inside.

Another object of my invention is to provide an improved structure and arrangement for guiding a sliding window sash for movement along a window frame, wherein the window sash may be detachably locked from sliding movement along the window frame and may be pivoted about the locking means therefor, to provide a means for pivoting the window for ventilation purposes and for washing the window from the inside.

A further object of my invention is to provide a window sash and frame therefor, wherein the guideways for the window sashes are in the form of recessed slideways extending vertically along the jamb of the frame, and wherein the slideways are engaged by guide rails recessed, within the sash and extensible therefrom into engagement with the slideways to afford a draft free structure accommodating the window to be readily raised and lowered.

Still another object of my invention is to provide a simple and efficient form of window structure having parallel spaced guideways extending along the jambs of the window frame and opening toward the sash, with slide rails recessed within the opposite rails of the sash for extension within the guideways, wherein the sash is provided with locking bolts released by the slide rails upon extension thereof from the sash, and engageable with cooperating sockets in the guideways upon retraction of the slide rails within the sash, so as to afford a means for locking the sash from vertical sliding movement and a pivot support means for the sash, accommodating the sash to be pivoted from the inside for ventilation purposes and for washing from within.

These and other objects of my invention will appear from time to time as the following specification proceeds and with reference to the accompanying drawings wherein:

Figure 1 is a transverse sectional view taken through a window structure constructed in accordance with my invention, and showing the window sashes in outwardly extended pivoted positions by broken lines;

Figure 2 is a horizontal sectional view taken substantially along line II—II of Figure 1;

Figure 3 is a fragmentary front end view of the lower sash and guideway of the window structure with certain parts broken away and certain other parts in vertical section in order to show the retractable slide rails extending within the channel slides and to show a locking bolt therefor in a released position;

2

Figure 4 is a fragmentary sectional view taken substantially along line IV—IV of Figure 3;

Figure 5 is a fragmentary sectional view taken substantially along line V—V of Figure 3;

5 Figure 6 is a view of the upper window sash, with parts thereof broken away and certain other parts shown in vertical section in order to illustrate the release for the slide rail for the upper window sash; and

10 Figure 7 is a sectional view taken substantially along line VII—VII of Figure 6.

In Figures 1 and 2 of the drawings, a window frame structure is shown, which may comprise a lower sill 10, a top head rail 11, and parallel spaced jambs 12, 12 having guideways 13 and 14 extending vertically therealong.

15 The guideway 13 may have the usual blind stop 15 extending along the outer side of the window frame inwardly from the jamb thereof, and may be stepped to be slidably engaged by a stepped side rail 16 of an upper window sash 17. The guideway 14 for a lower window sash 19 may have a shoulder 20 formed therein, along which the outer side of a side rail 21 for the lower sash may slide. The guideway 13 may also be stepped, to be slidably engaged by an outwardly stepped portion 23 of the side rail of the lower sash 19.

20 25 It should here be understood that the shoulder 20 takes the place of the usual parting strip to avoid interfering with inward swinging movement of the upper sash 17.

Along the lower part of each guideway 14 and recessed within the jamb 12 is a channel slideway 24, extending 30 therealong for the full length of the guideway 14 and adapted to be slidably engaged by a retractible slide rail 25, extensible from a channel-like housing 27, recessed within and extending vertically along each vertical side rail 21 of the lower sash 19.

35 40 It should here be understood that both side rails of the sash 19 have a similar channel-like housing 27 within which may be retracted a slide rail 25, and that since the construction on both sides of the window is the same, one side of the window only, need herein be shown and described in detail.

45 The channel slideway 24 is shown as having a plurality of sockets 29, 29 recessed therein to be engaged by a bolt 30, slidably mounted in the side rail 21 of the window sash, to lock the sash from vertical movement along the guideways 14, 14 and accommodate the sash to be pivoted inwardly about the axes of the bolts 30, 30.

50 55 Each bolt 30 is shown as being slidably mounted within a socket 31 extending inwardly from the base of the channel-like housing 27, and in an outwardly spaced cover plate 33 for the upper portion of said channel-like housing. The bolt 30 is likewise shown as extending through a release arm 34 secured thereto as by a pin 35. The release arm 34 is shown as depending from the bolt 30 into position to be engaged by an inturned upper end 59 of the slide rail 25 to retract the bolt 30 from the socket 29 as said slide rail is extended into engagement with the slideway 24, as will hereinafter be more fully described as this specification proceeds.

60 65 A spring 36 is shown as being interposed between the inner wall of the channel-like housing 27 and the inner side of the arm 34 to bias the bolt 30 in an extended position relative to the side rail 21 of the sash 19 to engage the socket 29.

65 70 Each slide rail 25 is shown in Figures 3 and 5 as being mounted in the channel-like housing 27 for extensible movement therefrom on parallel links 40, 40. As shown in Figure 5 the slide rail 25 is of a channel-like form, opening toward the base of the housing 27 and having the links 40, 40 extending within the open portion thereof and pivotally secured thereto as by pivot pins 43, 43. The inner ends of the links 40, 40 are shown as being pivoted to the base of the housing 27 on pivot pins 45, 45, ex-

tending through the outwardly extending vertical legs of angle brackets 46, 46. Said angle brackets are secured to the base of the housing 27, as by rivets 47.

The housing 27 is shown as having parallel inwardly extending guide portions 49, 49 spaced inwardly from the outer walls thereof and slidably extending along opposite sides of the slide rail 25 into sliding engagement therewith, to seal the sash to the window jamb.

A tension spring 50 is shown as being provided, to bias the slide rail 25 into an extended position from the channel-like housing 27. As herein shown, the spring 50 is secured at one of its ends to an ear 51 extending outwardly from the base of the channel-like housing 27 and at its opposite end to an ear 53 extending inwardly from the rail 25.

The lower end of the rail 25 is shown as extending angularly inwardly toward the base of the housing 27, and as being guided in an arcuate slot 55 formed in a face plate 56, which may be secured to the outside of the side rail of the sash. As herein shown a pin 57 is connected with the lower end of the slide rail 25, and extends outwardly through the arcuate slot 55, and has a key 59 on its outer end. The key 59 is of a convenient size and is in position to be grasped by the hand, to retract the slide rail 25 within the channel-like housing 27 upon downward pressing movement on said key. Downward pressing movement on the key 59 will release the upper in-turned end portion 39 of the slide rail 25 from the arm 34 and in turn release the bolt 30 to engage the desired socket 29, to lock the sash from vertical movement and to form a horizontal pivot therefor. The pin 57 may be threaded on the slide rail 25, as shown in Figure 4 and the key 59 may be turned to tighten said key against the face plate 56 and hold the slide rail 25 in a retracted position.

The upper sash 17 is shown as having a channel-like housing 60 recessed within and extending along each side rail thereof. The channel-like housing 60 is like the housing 27 except that it opens from the bottom of the sash to afford a means for retractably moving a slide rail 61 within said housing to release a bolt 63 to engage a socket 64 in a channel slideway 65 for the upper sash. The slideway 65 extends vertically along the guideway 13 for the entire length thereof.

The slide rail 61 is like the slide rail 25 and is pivotally mounted for retractable movement within the housing 60 on parallel links 66, 66 horizontally pivoted to the base of said housing on angle brackets 67, 67. A tension spring 69 is also provided to extend the slide rail 61 from the housing 60 within its cooperating channel slide 65.

The slide rail 61 has an inwardly inclined lower end portion 70 to which is pivoted a depending link 71 on a pivot pin 72. The link 70 is shown as extending through a slot 75 in a lower intermediate wall portion 76 of the housing 60 and as being retained between vertically spaced ears 73 and 74 extending inwardly from the base of the housing 60, when the slide rail 71 is in a retracted position. A ring 77 is shown as being connected to the lower end of the link 70 and depending therefrom. The ring 77 affords a means to be grasped by the finger to retract the slide rail 61 from the slide 65 into the housing 60, and release the bolt 63, to engage a socket 64. The ring 77 may also hold the rail 61 in a retracted position when abutting the bottom of the ear 74.

It should further be noted that the rails 25 and 61 are biased into engagement with the respective channel slideways 23 and 65 with sufficient frictional resistance to hold the window in position during raising or lowering thereof, but still enable the window to be easily raised and lowered.

It may be seen with reference to Figure 1 that when it is desired to swing the sashes 17 and 19 outwardly, that the lower sash 19 is moved to the upwardly extended position shown by broken lines, to accommodate the bolts 30 in each side rail of the sash to engage the upper sockets

29, 29. The upper sash is likewise moved downwardly along its guideway to accommodate the bolts 65, 65 to engage the lowermost sockets 64, 64. When the sashes are in these positions the slide rail 25 is released from the pin 30 by depressing the key 57 downwardly along the slot 55 to accommodate the bolt 30 to enter the socket 29.

The fingers are also inserted within the rings 77, 77 to retract the slide rails 61, 61 within the housings 60, 60 and accommodate the pins 63, 63 to engage the corresponding sockets 64, 64.

When it is desired to maintain the sashes 16 and 19 in the inwardly hinged open positions shown by dotted lines in Figure 1, a toggle link or other locking link arrangement (not shown) may be provided to hold the sashes in the desired angular positions.

It may be seen from the foregoing that a novel and improved form of window frame structure has been provided in which the window is sealed by a slide rail extensible within a channel guide extending along the window jamb, and is locked by a spring urged bolt which is automatically withdrawn when the rail is extended into the channel for vertical movement therealong.

It may further be seen that the window sash may be slidably moved along its frame and held in position therein by engagement of the rail with the channel guide and may readily be pivoted about its locking bolts, to open the window, for ventilation and to enable the window to be cleaned from the inside.

It will be understood that the device of my invention is adapted for either metal or wooden sashes and frames, and that while two forms of releases are herein shown, the same releases are suitable for use in either the upper or lower sashes.

It will be understood that modifications and variations may be effected without departing from the spirit and scope of the novel concepts of the present invention.

I claim as my invention:

1. A window structure comprising a frame having jambs with parallel guideways extending therealong, window sashes guided along said guideways, means for guiding each window sash for vertical movement along the respective guideway and mounting the sash for pivotal movement with respect to the frame about a horizontal axis, comprising a vertically extending channel slideway recessed within each guideway, sliding rails retractable within the sides of said sashes and extensible therefrom within said channel slideways during window raising and lowering movement, locking bolts mounted in said sashes and biased for engagement with cooperating sockets within said channel slideways, for holding the sash from vertical movement and accommodating pivotal movement of the sash, said slide rails having operative connection with said locking bolts to withdraw said bolts when the rail is fully extended into said channel slideway for vertical movement therealong.

2. A detachable window structure comprising a frame having facing jambs having a plurality of adjacent parallel guideways extending therealong, each guideway including a vertically extending channel slideway recessed within the associated jamb, a window sash guided for movement along each guideway, sliding rails retractable within opposite sides of each sash and extensible therefrom into said channels for guiding the window during window raising and lowering, spring means biasing said slide rails in extended relation with respect to said sash, bolts extensibly mounted in opposite sides of said sash for locking engagement with said channel slideways for holding the sash from vertical movement and accommodating pivotal movement of the sash, and engaging connections between said slide rails and bolts, releasing said bolts upon extension of said slide rails within said slide ways.

3. A window structure comprising a frame having facing jambs with guideways extending vertically therealong and window sashes vertically movable therealong,

means guiding each sash for vertical movement along the respective guideways and mounting said sash for ready detachment therefrom comprising a channel slide-way extending vertically along each guideway, a slide rail extending along each side of said sash and mounted for retractible movement with respect thereto, a bolt mounted in each side rail of the sash and spring biased to extend therefrom, means for extending said slide rails within said channel sideways, and other means operated by extension of said slide rails, for releasing said bolts, and maintaining said bolts in retracted position against the bias thereof.

4. A window frame structure comprising a frame having facing jambs having a plurality of adjacent parallel guideways extending therealong, each guideway having a vertically extending channel slideway recessed therein and extending vertically therealong, said channel slideway each having at least one socket therein, a window sash guided in each of said guideways, each sash having parallel side rails and slide rails extending therealong and mounted therein for retraction therein and for extension therefrom into said channel slideways, for guiding the sash for raising and lowering movement, spring means biasing said slide rails for extension from said sash, a bolt mounted in each side rail of the sash and spring biased to extend therefrom, means for extending said slide rails from said sashes within said channel slideways, and operative connections between said slide rails and bolts, retracting said bolts against their bias upon extension of said slide rails within said slideways to accommodate window raising and lowering movement.

5. A detachable window frame structure comprising a frame having facing jambs having a plurality of adjacent parallel guideways extending therealong, each guideway having a recessed vertically extending channel slideway extending therealong, a window sash guided in each of said guideways, and having parallel slide rails recessed within said side rails and mounted for extensible movement therefrom into sliding engagement with said channel slideways, said slideways having at least one socket therein, a bolt mounted within each side rail and having an arm extending therefrom toward an associated slide rail, a spring biasing said bolt in an extended position, and means extending said slide rails into engagement with said arms to retract said bolts, upon extension of said slide rails within said slideways, and accommodate window raising and lowering movement.

6. In a window frame structure having a pair of facing jambs having guideways extending therealong and including outwardly opening channel slideways extending for the length thereof, a window sash having parallel spaced side rails, means guiding said sash for movement along said guideways and for pivotal movement with respect thereto comprising a channel-like housing recessed within the side rails of the sash and opening toward said guideways, slide rails retractible within said housings, parallel links pivotally connecting said side rails to said housing, means extending said side rails from said housing into slidable engagement with said channel slideways, and the means locking said sash from movement along said channel slideways and affording a pivot means for the sash, and comprising sockets recessed within said channel slideways and bolts slidably mounted in said housings for engagement with said sockets, and an operative connection between said slide rails and said bolts, releasing said bolts by extension of said slide rails within said channel slideways.

7. In a window frame structure having a pair of facing jambs having guideways extending therewithin said channel slideways, including outwardly opening channel slideways extending for the length of said guideways, a window sash having parallel spaced side rails; means guiding said sash for movement along said guideways and for pivotal movement with respect thereto comprising slide rails extensible from the side rails of said sash, a channel-like housing

recessed within the rails of said sash and opening toward said guideways and forming a housing and support for said slide rails, parallel links pivotally connected to said housing and having said side rails connected thereto,
5 spring means extending said slide rails from said housing into slidable engagement with said channel slideways, and means controlled by extensible and retractable movement of said slide rails for locking the sash from movement along said guideways and affording a pivotal mounting therefor comprising at least one locking socket recessed within each channel slideway, locking bolts slidably carried by said housing for engagement with said sockets, spring means extending said bolts into engagement with said sockets, and other means on said bolts
10 15 engageable with said slides for withdrawing said bolts from said sockets upon extension of said slide rails within said channel slides.

8. In a window frame structure having a pair of facing jambs having guideways extending therealong including outwardly opening channel slideways extending for the length of said guideways, a window sash having parallel spaced side rails, means guiding said sash for movement along said guideways and for pivotal movement with respect thereto comprising slide rails extensible from the side rails of said sash, a channel-like housing recessed within the rails of said sash and opening toward said guideways and forming a housing and support for said slide rails, parallel links pivotally connected to said housing and having said side rails connected thereto, spring means extending said slide rails from said housing into slideable engagement with said channel slideways, and means controlled by extensible and retractable movement of said slide rails for locking the sash from movement along said guideways and affording a pivotal mounting therefor comprising at least one locking socket recessed within each channel slideway, locking bolts slidably carried by said housing for engagement with said sockets, spring means extending said bolts into engagement with said sockets, and other means on said bolts engageable with said slides for withdrawing said bolts from said sockets upon extension of said slide rails within said channel slides, and means retracting said slide rails within said housing and accommodating said bolts to engage said sockets comprising links depending from said slide rails and accessible from the bottom of said housing and sash.

50   9. In a window frame structure having a pair of facing jambs having guideways extending therewith including outwardly opening channel slideways extending for the length of said guideways a window sash having parallel spaced side rails, means guiding said sash for movement along said guideways and for pivotal movement with respect thereto comprising slide rails extensible from the side rails of said sash, a channel-like housing recessed within the rails of said sash and opening toward said guideways and forming a housing and support for said slide rails, parallel links pivotally connected to said housing and having said side rails connected thereto, spring means extending said slide rails from said housing into slidable engagement with said channel slideways, and means controlled by extensible and retractable movement of said slide rails for locking the sash from movement along said guideways and affording a pivotal mounting therefor comprising at least one locking socket recessed within each channel slideway, locking bolts slidably carried by said housing for engagement with said sockets, spring means extending said bolts into engagement with said sockets, other means on said bolts engageable with said slides for withdrawing said bolts from said sockets upon extension of said slide rails within said channel slides, and means for retractably moving said slide rails within said housings and releasing said locking bolts to engage said sockets, comprising arcuate guides in said side rails of the sash, in communication with the interior of said housing,

slidable guiding connections between said slide rails and guides comprising a guide pin secured to each slide rail and guided along said guide, and means on said pins affording a means for retractably moving said side rails along said arcuate guides.
